WINDOW SCREEN HOOK

Richard S. Moore, Dallas, Tex.

Application May 15, 1950, Serial No. 162,119

1 Claim. (Cl. 292—87)

1

This invention relates to a window screen hook, and has for one of its objects the production of a simple and efficient resilient hook which will fasten a screen frame to a window frame with a spring tension, so as to prevent rattling of the screen frame after it is placed in position upon the window frame.

A further object of this invention is the production of a spring tension hook which may be easily and conveniently operated to securely fasten a window screen frame to a window frame and which will hold the screen under a spring tension relative to the window frame.

Other objects and advantages of the present invention will appear throughout the following specification and claim.

In the drawing:

Figure 1 is a fragmentary vertical sectional view through a window screen showing the same secured to a window frame by means of the spring tension or resilient hook;

Figure 2 is a fragmentary side elevational view of a window screen illustrating the position of the hook when it is in an inoperative position;

Figure 3 is a front elevational view of the hook detached from a supporting window screen frame; and

Figure 4 is a side elevational view of the hook detached from a supporting window screen frame.

By referring to the drawing, it will be seen that 10 designates a conventional window screen frame, which is adapted to be supported upon a conventional window frame 11. A specially constructed spring tension hook 12 is secured to the inner face 13 of the screen frame 10 by means of a screw or other suitable fastening means 14. This screw 14 passes through an eye 15 at the upper end of the hook 12, and this eye 15 fits flat against the inner face 13 of the screen frame 10, as shown in Figures 1 and 2 of the drawing. The eye 15 is connected to an integral depending shank 16 from which extends a laterally and downwardly inclined portion 17. An inwardly and downwardly inclined portion 18 depends from the portion 17 and is inclined inwardly toward the central longitudinal axis of the hook 12. The portions 17 and 18 define a laterally extending V-shaped brace to resist lateral twisting strain upon the eye 15 and to provide a relatively broad abutment area. The portion 18 engages an integral forwardly extending coil 19 which extends longitudinally of the central axis of the hook 12 and at right-angles to the eye 15. The coil 19 terminates in a depending tension anchoring arm 20 which is provided at its lower end with an anchoring pin 21 engaging hook portion 21.

2

An anchoring pin 22 is secured to the window frame 11 preferably at the side thereof, as shown in Figure 1, and is inset at a proper distance from the inner face of the window screen frame 13 which window screen frame abuts the outer face of the window frame 11. The tension anchoring arm 20 is adapted to be swung inwardly and away from the screen frame 10 so that the hook 21 engages the anchoring pin 22 when the screen frame 10 is secured to the window frame 11, thereby securely anchoring the screen under a spring tension upon the window frame 11. This is made possible by the fact that the eye 15 is rigidly anchored upon the inner face of the screen frame 10 and the arm 20 is carried by the free end of the coil 19. The coil 19 is adapted to swing the hook 21 of the arm 20 against the frame 10 when the hook 21 is released from the anchoring pin 22.

It should be noted that the angular portions 17 and 18 are arranged in diverging relation and fit flat against the inner face 13 of the frame 10 and are offset laterally relative to the longitudinal axis of the hook 12 for aligning the eye 15 with the hook 21 and to resist lateral twisting strain upon the hook 12 by the flat contact with the inner face 13 of the frame 10. It should also be noted that the coil 19 extends in a plane at right-angles to the plane of the eye 15 and is in longitudinal alignment with the central axis of the eye 15. The hook 21 also is in alignment with the plane of the coil 19 so as to efficiently fit over the anchoring pin 22 to hold the screen frame 10 snugly against the window frame 11 and thereby prevent the screen from rattling when placed in position. As many tension hook fasteners as may be desired may be used to hold the screen frame in position.

Certain detail changes in mechanical construction may be made in the structure of the hook without departing from the spirit of the invention so long as such changes fall within the scope of the appended claim. It should be understood that the hook may be reversed if desired, to engage a pin above the hook, within the scope of the invention.

Having described the invention, what I claim as new is:

A new article of manufacture comprising a tension hook for holding a window screen frame from rattling upon a window frame, said tension hook having an anchoring eye at one end adapted to fit flat against one face of a window screen, an integral depending shank connected to said eye, a laterally extending portion carried by said shank, an inwardly extending portion connected

to said laterally extending portion, thereby defining a laterally extending brace having a relatively broad abutment area to resist lateral twisting strain upon said eye of said hook, the brace extending laterally of the longitudinal axis of 5 said shank, a coil carried by the extremity of said inwardly extending portion and arranged in alignment with the central axis of the anchoring eye in a plane at right angles to the anchoring eye, the coil terminating in an anchoring pin 10 engaging tension arm, and said arm having an inturned pin engaging hook portion at the extremity of the arm and in the same plane as said coil.
